UNITED STATES PATENT OFFICE

WALTER S. MAYER, OF BEAVER, PENNSYLVANIA, ASSIGNOR TO MAYER CHINA COMPANY, OF BEAVER FALLS, PENNSYLVANIA, A CORPORATION OF PENNSYLVANIA

DESIGN FOR A PLATE OR SIMILAR ARTICLE

Application filed March 8, 1932. Serial No. 43,132. Term of patent 14 years.

To all whom it may concern:

Be it known that I, WALTER S. MAYER, a citizen of the United States, residing at Beaver, in the county of Beaver and State of Pennsylvania, have invented a new, original, and ornamental Design for a Plate or Similar Article, of which the following is a specification, reference being had to the accompanying drawing, forming part thereof.

In the drawing:

The figure is a face view of the article, showing my new design, the plate being broken away at one side for marginal clearance, and having the ornamentation shown completed around the border.

I claim:

The ornamental design for a plate or similar article, as shown and described.

WALTER S. MAYER.
